UNITED STATES PATENT OFFICE.

ZEPHIREN DUCHEMIN, OF HAVERHILL, MASSACHUSETTS.

DESIGN FOR A HAMMER.

SPECIFICATION forming part of Design No. 23,169, dated April 3, 1894.

Application filed March 3, 1894. Serial No. 502,284. Term of patent 7 years.

To all whom it may concern.

Be it known that I, ZEPHIREN DUCHEMIN, of Haverhill, in the county of Essex and State of Massachusetts, have invented a new and original Design for a Hammer, of which the following is a full, clear, and exact description.

Reference is to be had to the accompanying drawings forming a part of this specification, in which similar letters of reference indicate corresponding parts in both the figures.

Figure 1 is a side elevation of a hammer embodying my design; and Fig. 2 an end elevation thereof.

The leading feature of my design consists in the configuration of the hammer head, the same having two faces, one round and the other oval, disposed at an angle to each other, and projecting laterally at all sides beyond the lines of the shank or cross bar that joins them.

In detail, the shank or cross bar *a*, of the head is squared at the center, and approximately round in cross section at its ends, and the lines of such round ends merge into the rear sides of the faces *b*, *c*, that project laterally at all sides beyond the shank. The faces *b*, *c*, are disposed in planes at an angle to each other and are of increasing thickness from their convergent to their divergent sides. 25 The face *b* is flat and is round as viewed from the front or back thereof and the face *c* is approximately convexed, that is, it is protuberant on irregular curved lines, and is oval as viewed from the front. 30 35

I claim—

The design for a hammer herein shown and described.

ZEPHIREN DUCHEMIN.
